UNITED STATES PATENT OFFICE.

ALLIOTT VERDON ROE, OF BURSLEDON, NEAR SOUTHAMPTON, AND REGINALD JOHN PARROTT, OF HEDGE END, NEAR SOUTHAMPTON, ENGLAND.

STABILIZING-PLANE ON AERIAL CRAFT.

1,336,161.

Specification of Letters Patent.

Patented Apr. 6, 1920.

Application filed January 4, 1919. Serial No. 269,654.

To all whom it may concern:

Be it known that we, ALLIOTT VERDON ROE and REGINALD JOHN PARROTT, subjects of the King of Great Britain, residing at 5 Bursledon and Hedge End, respectively, near Southampton, in the county of Hampshire, England, have invented certain new and useful Improvements in Stabilizing-Planes on Aerial Craft, of which the following is a specification.

This invention relates to improvements in and connected with hinged stabilizing planes on aerial craft, and has for its object to provide improved means for balancing such 15 hinged planes both mechanically and aerodynamically.

In accordance with current practice in aircraft construction, stabilizing planes generally consist in aerofoils hinged at their 20 leading edges to the rear of the fixed supporting surfaces—of which, in normal flight, they constitute a part; when such an aerofoil is deflected from its normal attitude of flight the total air pressure acting upon 25 it is considerable and unless it be so pivoted as to be substantially balanced (aerodynamically) about its pivotal axis, a relatively large force has to be exerted on its control members to effect a movement.

This invention consists in providing 30 means for balancing a hinged aerofoil of the type described in such a way as to obviate the aerodynamic difficulties hereinbefore alluded to, and embraces a separate auxiliary balancing plane stayed to the hinged member in such a manner that said auxiliary plane and said hinged stabilizing member lie on opposite sides of an approximately vertical plane through the hinge 35 pivot of the latter. Now in order that our invention may be more readily understood reference is made hereinafter to the accompanying sheets of drawings, in which:—

Figure 1 is an end elevational view of an 40 aeroplane wing having an aileron furnished with an auxiliary balancing plane, in accordance with the invention; Fig. 2 is a front elevational view and Fig. 3 a plan view of a portion of the wing and its attachments illustrated in Fig. 1; Fig. 4 is a side elevational view and Fig. 5 a plan of a tail unit, whereof the rudder and elevators are balanced by duplicate auxiliary planes; and Fig. 6 is a view taken substantially on

line A—B of Fig. 5, looking in the direction 55 of arrow X, and shows the movable aerofoils of the tail in front elevation.

Referring to these drawings, and particularly to Figs. 1-3 thereof, the numeral 1 designates an aeroplane wing, having 60 hinged to it, in the usual manner, an aileron 2 and, in accordance with our invention, we mount upon this aileron—preferably upon the upper surface thereof—one or more struts 3 inclined so as to overhang the main 65 aerofoil and adapted to carry an auxiliary plane or planes 4, for balancing said aileron. In Fig. 1 the auxiliary plane 4 is shown as of a cambered section by reason of which, in normal flight, it experiences a lift reaction 70 due to its passage through the air, thereby contributing to the vertical sustaining forces acting on the machine. It may, however, if desired, have a flat or a streamline section, and examples of the latter form are herein- 75 after described and illustrated in connection with a tail unit.

For ailerons of ordinary proportions, it is generally convenient to employ one auxiliary plane 4, carried by two or, at most 80 three supporting struts 3 and one or more of these struts 3 may perform the function of an aileron actuating lever. This arrangement is shown in Figs. 1-3 wherein the numerals 5 indicate aileron control cables 85 connected by turnbuckles 6 to the struts 3 and passing over pulleys 7 to the control stick of the machine. It will of course be apparent that the underside of the aileron 2 is provided either with an actuating lever 90 of conventional form or with an attachment for an inter-aileron wire 8.

The application of our invention to the rudder and elevators of a tractor aeroplane is illustrated in Figs. 4-6. The fuselage 24 95 has a fixed vertical fin 25 and to this is hinged a rudder 26, while to sides of said fuselage are attached the fixed tail planes 27 having elevator flaps 28 hinged to them.

In order to balance the rudder 26 duplicate auxiliary balancing planes 29—preferably of streamline section—are attached to it by means of inclined struts 30, and these auxiliary planes are symmetrically disposed, one on each side of the rudder so 105 that the forces due to the aerodynamic resistance, or "drag" may be balanced, in normal flight, about the pivotal axis of the rud-

der. One opposed pair of struts 30 may conveniently functionate as rudder actuating levers, and to this end may have lugs or extensions passing through the auxiliary 5 planes to provide attachments 31 for the rudder control cables 32.

In this case of a streamline or non-lifting tail such as that illustrated in the drawings, the elevators 28 are balanced in similar 10 manner to the rudder, by means of duplicate streamline auxiliary planes 33 carried by inclined struts 34. Where however, a cambered tail is employed the method of balancing the elevators is the same as that 15 hereinbefore described in connection with ailerons, *i. e.*, each elevator carries only one auxiliary balancing plane which is preferably of a cambered or lifting section.

In the drawings attachments 35 for the 20 elevator control cables 36 are shown in the plane of the inner sets of struts 34, from which they preferably extend.

Though specifically described in relation to the hinged stabilizing planes of an aero- 25 plane, it will be understood that our invention is applicable to the hinged steering or stabilizing members of airships, or to any analogous hinged aerofoils.

What we claim as new and useful and desire to secure by Letters Patent is:—

1. In a device of the class described, the combination of a hinged stabilizing plane, a separate auxiliary balancing plane, and a rigid stay connecting them together in such 35 a way that they lie substantially on opposite sides of a common axis of rotation.

2. In a device of the class described, the combination of a hinged stabilizing plane, two separate auxiliary balancing planes dis- 40 posed one on each side of the said stabilizing plane and each connected thereto by a rigid stay, so that movement of the stabilizing plane about its pivot causes movement of one balancing plane in opposite direction but 45 in similar phase to that of the other, whereby both balancing planes serve to counter-

act the aerodynamic pressure due to movement of the said stabilizing plane.

3. In a device of the class described, the combination of a hinged stabilizing plane, 50 one or more rigid stays forming the levers by which the stabilizing plane is operated, a separate auxiliary balancing plane connected to the said levers so as to be supported in normal flight forward, or substantially for- 55 ward of the pivot of the stabilizing plane, and means for actuating the said levers.

4. The combination in an aeroplane of stabilizing planes pivoted to the fixed main planes, separate auxiliary balancing planes, 60 rigid stays connecting the said stabilizing and balancing planes so that the balancing planes are supported substantially forward of the pivots of the stabilizing planes, a vertical rudder plane, vertical balancing 65 planes, rigid stay connecting the said bal- ancing planes one on each side of the said rudder plane so that they are supported for- ward of the pivot of the said rudder plane, elevating planes, duplicate auxiliary planes, 70 rigid stays supporting the said planes one above and one below the said elevating planes so as to be substantially forward of the pivots of the latter and means for act- 75 uating respectively certain of the rigid stays of the main stabilizing planes, the rudder plane, and the elevating planes, so that the said stays are actuated to operate the said planes for the control of the aeroplane, each of the said control planes being balanced 80 aerodynamically by the balancing planes as regards the pressures set up by deflection of the said control planes from their normal attitude of flight.

In testimony whereof we affix our signa- 85 tures.

ALLIOTT VERDON ROE.
REGINALD JOHN PARROTT.
